UNITED STATES PATENT OFFICE

AUGUST P. MUNNING, OF BROOKLYN, NEW YORK, ASSIGNOR TO A. P. MUNNING & CO., OF NEW YORK, N. Y., A CORPORATION OF NEW JERSEY.

ANODE.

Application filed December 5, 1921. Serial No. 519,942.

To all whom it may concern:

Be it known that I, AUGUST P. MUNNING, a citizen of the United States, a resident of Brooklyn, in the county of Kings and State 5 of New York, have invented a certain new and useful Improvement in Anodes, of which the following is a specification.

The invention has for an object to provide an anode for use in electro-lytic apparatus which will combine the quality of maximum surface exposure to the bath with minimum weight or volume, and which will be of such structure as to be capable of being manufactured by easy shaping operations into various sizes or shapes such as might be desired for different classes of work.

The invention also aims to secure high and uniform conductivity throughout the anode 20 as well as to eliminate waste in manufacturing and using or in adapting the same to different purposes. Further objects and advantages will be in part obvious and in part specifically pointed out in the description hereinafter contained, which, taken in connection with the accompanying drawings, discloses a preferred embodiment thereof; such embodiment, however, is to be considered merely as illustrative of its principle. In the drawings:

Fig. 1 is a side view partly in section of an anode constructed in accordance with the invention.

Fig. 2 is an end view of the structure 35 shown in Fig. 1.

In order to provide an anode which will have large surface exposure to the bath, the body thereof is provided with one or more ridges 1, which are directed obliquely to its 40 longitudinal axis and thus break up the surface of the anode into a plurality of raised portions and depressions which materially increases its effective area. In the illustrated embodiment a single ridge 1 of the 45 character above mentioned is employed, and extended spirally around the surface of the anode from end to end, thus obtaining a larger effective area or exposure than would be the case with longitudinal or transverse 50 ridges of similar size.

Although an anode of the above character may be made by casting, one of its important advantages is due to the fact that ridges of the character above mentioned 55 may be provided by less expensive or less

difficult metal shaping operations and permitting the use of metal in standard commercial sizes and forms. The anode shown in the drawing consists of a metal bar 2 which is suitably shaped into spiral form, 60 for example by winding it over a mandrel; although it will be understood that the proper shape of the anode may be obtained by other operations such as drawing, extruding or rolling. I prefer to make up the anode 65 of a metal bar of polygonal cross section and to shape the same into the desired form so with relation to its cross section that the oblique ridge 1 will be formed by the sides 4 and 5 of the cross sectional polygon, which 70 sides converge outwardly to form the ridge, the inner side or sides of such cross sectional polygon leaving a hole 7 within the anode. An anode as above described, therefore, may be easily constructed of minimum 75 weight by employing a metal bar of such size as to leave the hole 7 therein sufficiently large to avoid the use of an undue amount of metal, while the spiral ridge will provide adequate exposure to the bath. It will 80 be understood that an anode as above described can be made without waste of any desired length or size, or cross sectional area, since, although the illustrated embodiment is cylindrical, no material difficulty would be involved in making the same of any other shape likely to be desired.

Since the metal bar 2 extends throughout the whole length of the anode, the latter 85 also will be of uniform and high conductivity throughout, no high resistance joints or the like being involved between the portions provided to increase the surface exposure. The anode is entirely self-supporting and sustaining, no spine or core being necessary to hold the oblique ridges in place, and since, as above described, the anode may be made up from metal in bar form, the invention is not limited in regard to the metal which may be employed, but any material adapted for use as an anode, such as nickel, copper, zinc, brass or other composition may be used without difficulty in the shaping operations.

I prefer to secure the anode to its support by a detachable wedge or expansion device co-operating with hole 7 in the anode, thereby rendering the anodes and their supports interchangeable, or the same anode to be reversed with regard to its support,

which might be desirable, for example, if one end should be consumed more rapidly than the other, in which case the electrode can be turned upside down to obtain uniform consumption of the material thereof. In the present form of the invention, support 8 is screw-threaded and a tapered nut 9 engages the screw threads, while a collar 10 is slidable along the support above the nut previously described. Split sleeve 11 is interposed between the members 9 and 10 previously described, and has detents 12 and 13 at its upper and lower ends respectively which engage over projections 14 and 15 respectively on nut 9 and collar 10. The inner surface of split sleeve 11 is tapered, whereby if the support 8 be turned, nut 9 will be drawn upwardly and sleeve 11 wedged outwardly into firm engagement with hole or opening 7.

It will be noted that the anode support 3 and its attaching device need not extend more than a slight distance into the anode, and therefore, it is possible to avoid the use of special materials such as lead in connection with the support, since the latter and its attaching device may be kept above the surface of the bath without waste or undue electrical resistance of the material of the anode. The particular form of attaching device above described, however, should be considered merely as typical or illustrative of devices of this class.

The invention also embodies an anode which will eliminate waste in use by permitting partially consumed anodes to be attached to or supported from similar more perfect anodes, in such manner that consumption of the material of the partially consumed anode may then be completed. Continued use of an anode tends to cause it to taper toward its lower end, and an anode made in accordance with the present invention may be readily constructed to enable the tapered portion of a partially consumed anode to be inserted within the hole 7 of a similar more perfect anode, suitable means being provided whereby the partially consumed anode, inserted as above described, will be held in position until it has been completely consumed. In the illustrated form of the invention, the bar 2 is of rectangular cross section, whereby the inner sides 6 and 6^a of the cross sectional polygon of the bar converge to form an inner spiral ridge 16 of a pitch equal to that of the outer spiral ridge. Thus after an anode has become partially consumed, its tapered end may be inserted within the hole 7 at the bottom of a newer anode as shown in Fig. 1, until the outer ridge of the partially consumed anode engages the inner spiral ridge 16 of the newer anode, the ridges interengaging in such manner that a further slight rotation of the partially consumed anode

will cause it to be effectively locked to or supported by the newer anode until completely consumed.

While a specific embodiment of the invention has been shown, it will be obvious that many changes will be made therein without departing from the spirit of the invention as defined in the following claims.

I claim:

1. An anode for electro-lytic apparatus comprising a metallic member having a ridge on its periphery directed oblique to its longitudinal axis.

2. An anode for electro-lytic apparatus comprising a hollow metallic member having a ridge on its periphery directed oblique to its longitudinal axis.

3. An anode for electro-lytic apparatus comprising a metallic member having a ridge extending spirally around the periphery thereof.

4. An anode for electro-lytic apparatus comprising a hollow metallic member having a ridge extending spirally around the periphery thereof.

5. An anode for electro-lytic apparatus comprising a metal bar of spiral shape.

6. An anode for electro-lytic apparatus comprising a metal bar of spiral shape, adjacent turns of the spiral being substantially in contact with each other.

7. An anode for electro-lytic apparatus comprising a metal bar formed into a spiral, said bar being of polygonal cross section with sides converging outwardly to form a spiral ridge on the periphery of the anode.

8. An anode for electro-lytic apparatus comprising a metallic member having parts on the body thereof shaped to engage and support a partially consumed anode of similar type.

9. An anode for electro-lytic apparatus comprising a hollow member having spiral ridges of substantially equal pitch on its inner and outer surfaces.

10. A hollow anode for electro-lytic apparatus having raised portions and depressions on its outer surface, the inner surface of such anode being also provided with raised portions and depressions adapted to interfit with the outer raised portions and depressions of a similar partially consumed anode.

11. The method of making an anode for electro-lytic apparatus which comprises bending a metal bar of polygonal cross section into spiral form with an inner side of such polygon disposed substantially parallel to the longitudinal axis of the anode, and other sides of such polygon converging outwardly to form a spiral ridge of the periphery of the anode.

12. An anode for electro-lytic apparatus comprising a hollow metallic member, an anode support, and detachable means for se-

curing said support to said metallic member comprising an expansion device adapted to fit within the hollow of such member.

13. An anode for electro-lytic apparatus comprising a hollow metallic member, an anode support, and detachable means for securing said support to said metallic member comprising an expansion device adapted

to fit within the hollow of such member, said attaching device being located entirely in 10 the upper portion of the anode.

In testimony that I claim the foregoing, I have hereunto set my hand this 25th day of November, 1921.

AUGUST P. MUNNING.
